UNITED STATES PATENT OFFICE.

GEORGE A. McILHENNY, OF WASHINGTON, DISTRICT OF COLUMBIA.

DIP-PIPE.

SPECIFICATION forming part of Letters Patent No. 247,386, dated September 20, 1881.

Application filed July 6, 1881. (No model.)

To all whom it may concern:

Be it known that I, GEORGE A. McILHENNY, of Washington, in the District of Columbia, have invented certain Improvements in Dip-
5 Pipes, of which the following is a specification.

My invention relates to dip-pipes of gas apparatus; and it consists in a short dip-pipe or section descending through the top of the hydraulic main, and encircling the upper end of
10 the ascension-pipe, which, under my construction, rises through the bottom of the main, said dip-pipe being provided with a removable lid or cover, and with a valve, whereby communication may be established or cut off be-
15 tween its interior and the open space of the hydraulic main.

The accompanying drawing represents a vertical central section of my apparatus.

The object of my invention is to cheapen the
20 construction of the apparatus, to facilitate the cleaning or clearing of the pipes, and to provide means for instantly sealing or unsealing any dip-pipe of the series and its corresponding retort.

25 To this end I construct the parts as shown in the drawing, in which A represents the hydraulic main, B the ascension-pipe passing up through the bottom of the main and rising to a proper height above the liquid therein, and C the dip-pipe passing down through the top of the main, encircling the upper end of the ascension-pipe, and dipping into the liquid to a sufficient distance to effectually seal the pipe. Under this arrangement the gas arising
35 in the ascension-pipe will pass out at the top of the same and descend through the annular space *a* between said pipe and the encircling dip-pipe to the liquid, through which, unless other escape be afforded, it will force its way
40 beneath the lower end of the dip-pipe and up into the open space of the main, whence it will pass through the intermediate parts of the apparatus to the gas-holder.

For the purpose of permitting the ascension
45 and dip pipes to be readily cleaned or cleared of obstructions the latter is furnished with a removable lid, D, which may be secured in place in any suitable manner, but which is preferably formed with a beveled edge to fit a mouth
50 of corresponding form, and held to said mouth or seat by a screw, E, bearing upon it at the center, in the same manner as the lids of gas-retorts are secured in place.

In order that the dip-pipes may be readily

sealed or unsealed, I provide each with a valve, 55 F, in its side at a point above the liquid in the main, and furnish said valve with an operating-stem, G, which passes through a stuffing-box, H, and is preferably connected with an actuating-lever, I.

60 It will be seen that by simply opening or closing the valve free communication may be established or cut off between the ascension-pipe and the hydraulic main quickly and with ease, and without moving or adjusting the dip-pipe. It will also be seen that when the valve is closed the gas may escape beneath the end of the dip-pipe, as usual, though prevented from returning to the ascension-pipe by reason of the rise of the sealing liquid in the annular 65 space *a*, when the pressure from within the ascension-pipe ceases.

Under the above construction each retort of the entire series may be sealed or unsealed without affecting others of the series, and each 70 ascension-pipe may be readily reached for cleaning without removing the dip-pipe or disturbing the valve and its fixtures.

75 I am aware that the ascension-pipe has hitherto been arranged to pass up through the bottom of the hydraulic main; that the dip-pipe used therewith has been provided with a removable lid, and that a valve has been applied to a dip-pipe for the purpose of sealing and unsealing the same; hence I do not claim 80 these features *per se*; but

85 What I do claim is—

1. In combination with an ascension-pipe passing upward through the bottom of the hydraulic main, a dip-pipe descending through 90 the top of the main and encircling the ascension-pipe, and provided with a valve whereby communication may be opened or closed between the ascension-pipe and the main, substantially as set forth.

2. In combination with an ascension-pipe passing upward through the bottom of the hydraulic main, a dip-pipe descending through 95 the top of the main and encircling the ascension-pipe, provided with a removable lid, and with a valve, whereby communication may be established between the ascension-pipe and the main.

GEORGE A. McILHENNY.
